DESIGN FOR A BUTTON

Dudley H. Munger, Waterbury, Conn., assignor to
Globe-Superior Corporation, Abingdon, Ill., a
corporation of Illinois

Application April 2, 1935, Serial No. 56,182

Term of patent 7 years

To all whom it may concern:

Be it known that I, Dudley H. Munger, a citizen of United States of America, residing at 651 Cooke Street, Waterbury, in the county of New Haven and State of Connecticut, have invented a new, original, and ornamental Design for a Button, of which the following is a specification, reference being had to the accompanying drawing, forming part thereof.

In the drawing, Figure 1 is a front elevation of a button showing the design of my invention;

Figure 2 is a diametrical cross section on a slightly larger scale.

I claim:

The ornamental design for a button as shown and described.

DUDLEY H. MUNGER.
